BATTERY CLAMP DEVICE

Edward A. Duval, Easthampton, Mass.

Application September 13, 1933, Serial No. 689,224
Renewed November 15, 1934

6 Claims. (Cl. 173—259)

This invention relates to improvements in battery clamp devices and more particularly to means for clamping a connection to the terminal post of a storage battery.

5 The principal objects of the invention are directed to the provision of means to facilitate the clamping of a connection to the terminal post of a storage battery. According to special features of the invention there is provided a novel 10 clamping means which is constructed and arranged to facilitate ease in manipulation and security in the clamping operation.

A common connection used in connection with the terminal post of a storage battery consists 15 of a split clamp member having lugs through which a clamp bolt passes. By means of the bolt and its nut the lugs are drawn together so that the clamp member is caused to firmly embrace the post. Considerable difficulty is experienced 20 because it is necessary to turn the nut and the bolt by swinging a wrench in a vertical plane and there is very little, if any, room between the clamp and the top of the battery to permit this.

According to this invention, a clamping means 25 is provided which includes a clamp bolt for passing through clamp lugs which is arranged so that a wrench may be swung at some distance from the clamp and battery top and thereby not only is it possible to easily and readily manipulate the device, but the clamp is made secure on the terminal post.

Various novel features and advantages of the invention will be hereinafter more fully referred to in connection with the accompanying description 30 of the preferred form of the invention which for purposes of disclosure is illustrated in the accompanying drawing, wherein:

Fig. 1 is a plan view of a clamping device embodying the novel features of the invention.

40 Fig. 2 is a front elevational view of the device shown in Fig. 1.

Fig. 3 is a side elevational view of the same, and

Fig. 4 is a perspective elevational view of the wedge member of the device.

45 Referring now to the drawing more in detail the invention will be fully described.

A terminal post of a battery is shown at P which may be of the usual form and which as usual extends or may be considered as extending 50 upwardly from one of the cells of a storage battery. A clamp member 2 has a socket 4 at its rear side to receive the end of a cable 6 and its forward side is slotted at 8, there being a pair of ears such as 10 at either side of the slot 8. The ears are provided with openings to receive

a clamp bolt which in the form shown includes a body portion 12 passing through the openings in the lugs and a transverse, angularly disposed tail part 14.

Opposite ends of the bolt are provided with 5 screw threads, as shown, for receiving nuts 16 and 18.

A wedge member 20 is provided which has a central opening 22 receiving the tail 14 of the bolt and is arranged to easily slide on the tail 10 10. The wedge is provided with a slot 24 at one side of the central opening and a slot 26 at the other side, while there is a stop 25 to limit the lower position of the wedge relative to the bolt.

The nut 16 is set so that with the nut 18 more 15 or less loose, an inclined wedging face 23 of the wedge bears against the outermost side of the right hand lug 10. With this nut loosened the lugs 10 are as usual inclined to spread apart so that the clamp may be slipped on and off the 20 terminal post P.

When it is desired to secure the clamp to the terminal post and when it is in place as shown the nut 18 is turned which acts on the wedge 20 to force it downwardly so that its wedging 25 face bears against the outer side of the right-hand lug. With the nut 16 bearing on the outer face of the left-hand lug, the tightening of nut 18 forces the wedge downwardly to draw the lugs together and in that way the clamp securely 30 binds the terminal post.

When it is desired to loosen the clamp, the nut 18 is loosened to release the pressure on the wedge 20 and as the pressure is thus released, the lugs 10 spread apart so the clamp releases 35 the post. When desired, and in order to insure that the wedge is free of the lug, the tail 14 of the clamp bolt may be swung counterclockwise or swung to the left of the position shown in Fig. 3, whereupon the wedge is entirely free of the 40 lugs or the clamp so that the lugs may freely spread apart.

It will be noted that with the wedge and the tail of the bolt in the position shown, it is an easy matter to apply a wrench to the nut 18 45 and swing the same in a horizontal plane as distinguished from placing a wrench on a nut such as 16 or the head of a bolt and swinging it in a vertical plane. This facilitates the tightening of the clamp with ease.

The overall dimensions of the lugs or the distance from the outer face of one to the outer face of the other varies. The nut 16 provides a means of adjusting the bolt and wedge to various clamps and such adjustments may be made 50 55

as allows the minimum of rotation of the nut edge 18 to clamp and unclamp the post.

The clamp is caused to grip the terminal post with the desired pressure which of course tends to obviate corrosion and it is desired in some cases to make the wedge member 20 of non-ferrous material. That is, of some composition less likely to corrode in the presence of fumes and acid which is common with storage batteries.

10 Various changes and modifications may be made in the form of the invention without departing from the spirit and scope thereof and therefor I desire to be limited if at all by the appended claims rather than by the foregoing description. What I desire to claim and secure by Letters Patent of the United States is:

1. A device for use with the lugs of a clamp having aligned openings therethrough comprising, a bolt having a body portion for extending through the openings in the lugs and a tail extending angularly therefrom, both ends of the bolt being threaded, a nut on the threaded end of the main body portion of the bolt for abutting the outer face of one lug, a wedge member having an opening receiving the tail of the bolt and having an inclined face for bearing against the outer face of the other lug and a nut on the threaded end of the tail for bearing on said lug to move the same along the tail.

2. A device for use with the lugs of a clamp having aligned openings therethrough comprising, a bolt having a main body portion for extending through the openings in the lugs having a tail portion extending at right angles therefrom and both ends of the bolt being threaded, a nut on the threaded end of the main body portion for bearing against the outer side of one lug, a wedge slideable axially of the tail having a wedging face for bearing against the outer face of the other lug and a nut in threaded engagement with the end of the tail of the bolt for bearing on the wedge.

3. The combination with the spaced lugs of a battery post clamp having bolt openings therethrough of means for drawing the lugs together comprising, a bolt having a main body portion extending through the openings in the clamp lugs and a tail extending angularly therefrom at the outer side of one lug, the ends of said body portion and tail being threaded, a nut on the threaded end of the body portion for bearing on the outer face of one lug, a wedge member slideable on the tail having a wedging face for bearing on the outer face of the other lug, and a nut on the threaded end of the tail for urging said wedge axially of the tail and exerting pressure against said other lug.

4. The combination with the spaced lugs of a battery post clamp having bolt openings therethrough of means for drawing the lugs together comprising, a bolt having a main body portion extending through the openings in the clamp lugs and a tail extending angularly therefrom at the outer side of one lug, the ends of said body portion and tail being threaded, a nut on the threaded end of the body portion for bearing on the outer face of one lug, a wedge member slideable on the tail having a wedging face for bearing on the outer face of the other lug, a nut on the threaded end of the tail for urging said wedge axially of the tail and exerting pressure against said other lug, and means associated with said wedge and main body of the bolt to limit the movement of the former relative to the latter.

5. The combination with the spaced lugs of a battery post clamp having bolt openings therethrough of means for drawing the lugs together comprising, a bolt having a main body portion extending through the openings in the clamp lugs and a tail extending angularly therefrom at the outer side of one lug, the ends of said body portion and tail being threaded, a nut on the threaded end of the body portion for bearing on the outer face of one lug, a wedge member slideable on the tail having a wedging face for bearing on the outer face of the other lug, and a nut on the threaded end of the tail for urging said wedge axially of the tail and exerting pressure against said other lug, the said wedge being slotted at its lower side to receive the main body portion of the bolt.

6. The combination with the spaced lugs of a battery post clamp having bolt openings therethrough of means for drawing the lugs together comprising, a bolt having a main body portion extending through the openings in the clamp lugs and a tail extending angularly therefrom at the outer side of one lug, the ends of said body portion and tail being threaded, a nut on the threaded end of the body portion for bearing on the outer face of one lug, a wedge member slideable on the tail having a wedging face for bearing on the outer face of the other lug, and a nut on the threaded end of the tail for urging said wedge axially of the tail and exerting pressure against said other lug, the said wedge being slideable on the tail by means of an opening receiving said tail and being provided with a slot extending inwardly from said wedging face having a stop at its upper side for abutting the main body of the bolt to limit the movement of the wedge relative to the bolt.

EDWARD A. DUVAL.
